UNITED STATES PATENT OFFICE.

ROBERT T. LEWIS, JR., OF BRIDGEPORT, CONNECTICUT, ASSIGNOR TO
THE AMERICAN TUBE AND STAMPING COMPANY, OF BRIDGEPORT,
CONNECTICUT, A CORPORATION OF CONNECTICUT.

METAL VEHICLE-WHEEL.

No. 838,630.

Specification of Letters Patent.

Patented Dec. 18, 1906.

Application filed June 24, 1905. Serial No. 266,854.

To all whom it may concern:

Be it known that I, ROBERT T. LEWIS, Jr., a citizen of the United States, residing at Bridgeport, county of Fairfield, State of Connecticut, have invented a new and useful Metal Vehicle-Wheel, of which the following is a specification.

My invention relates more especially to the construction of what are termed the "hub-flanges" of vehicle-wheels made entirely of metal and using return-bend spokes; and my invention has for its object to produce a hub-flange of this character which shall be simple and inexpensive to produce, neat and attractive in appearance, in which the spokes shall be so firmly locked in the flange as to render movement in any direction impossible, thus insuring the greatest possible strength and rigidity to the wheel, which shall be so constructed as to provide an effective oil-guard, thus wholly preventing soiling of the clothing by contact with the hub, and which shall be adapted without change to either small or barrel hubs and for use upon either nut or nutless axles.

With these ends in view my invention consists in certain parts, improvements, and combinations, which will be hereinafter fully described and then specifically pointed out in the claims hereunto appended.

In the accompanying drawings, forming a part of this specification, Figure 1 is a longitudinal section of a barrel-hub complete, illustrating the use of my novel flanges in connection with a nutless axle. Fig. 2 is an enlarged outer face view of an outer flange detached. Fig. 3 is an inner face view of either an inner or outer flange detached. Fig. 4 is a face view of the inner or grooved disk detached, showing a special form of bend of the spokes and the manner in which the bends are socketed in the grooves. Fig. 5 is a vertical section of the outer disk in its assembled form, but detached. Fig. 6 is a vertical section of an inner disk with the sleeve turned outward. Fig. 7 is a similar view with the sleeve turned inward. Fig. 8 is a view similar to Fig. 1, illustrating the use of my novel flanges in connection with a nutless axle. Fig. 9 is a cross-section showing the wheel in place upon an axle, the axle-box and hub-barrel being in section and the outer disk

partly in section at the bend of the tongues; and Fig. 10 is an outer face view, partly broken away, of either an inner or outer flange detached, showing the use of my novel grooved inner disk in connection with the ordinary form of return-bend spokes.

A denotes an axle; B, an axle-box; C, a hub-barrel; D, outer flanges as a whole, and E inner flanges as a whole. It should be understood that I use the term "inner" and "outer" as applied to the flanges merely as a distinguishing term. The outer flanges are provided with oil-guards; the inner flanges are not; but flanges with or without oil-guards may be used, if preferred, at either end of the axle-box.

The flanges consist, essentially, of an inner disk 20 and an outer disk 21. The axle-box is provided near each end with a circumferential rib 22, against which the inner disk of the corresponding flange bears. Each inner disk is provided with an integral sleeve 23, which forms the bearing of the flange upon the axle-box. This sleeve may be turned outward, as in Fig. 6, or inward, as in Fig. 7.

In all of the forms the inner disk is provided in its face with a recess 36, which receives one end of a hub-barrel, as clearly shown in Figs. 1, 8, and 9. If an ordinary small hub is required, the hub-barrel is not used. If a barrel-hub is required, the barrel is simply placed between the flanges of the wheel, its ends engaging the depressions 36, and is rigidly locked in place in assembling by upsetting the ends of the axle-box, as at 31.

An important feature of construction of the inner disks is that each is provided with grooves which receive the bends of the spokes. In the form illustrated in Fig. 4 the inner disk is provided with a circumferential groove 24 and a series of radial grooves 25, leading into the circumferential groove. The spokes 27 lie in these grooves, the walls of the grooves supporting them and retaining them rigidly in place.

The spokes are of the return-bend type—that is, each pair of spokes is formed from a single piece of wire, at the mid-length of which is an inward or concave curve, as at 28, to correspond with the curvature of the circumferential groove, as clearly shown in Fig. 4.

This construction of the inner disk and spokes gives the greatest possible strength and rigidity to the flange, as it is impossible for the spokes to slip or move in any direction when the flange is assembled. The outer disk is provided with a series of notches 29, which receive the spokes, leaving between the notches tongues 30, which are curved over the edge of the inner disk between the 10 hubs, thereby locking the spokes and inner and outer disks rigidly and securely together and making the flange as a whole very much stronger than when made in the ordinary way. The flanges are locked to the axle-box by upsetting the ends of the axle-box against the ends of the sleeves of the flanges, as at 31, as clearly shown in Figs. 1 and 8, each flange being securely locked between a rib on the axle-box and the upset end of the 20 axle-box.

Each of the outer disks is provided with a central opening 32, whether formed with or without an oil-guard. In what I have termed "inner" flanges the outer face of the 25 inner disk lies substantially at right angles to the axis of the axle-box, and in what I have termed "outer" flanges the outer face of the outer disk is provided with an oil-guard 33, formed by stamping the metal outward in the form of a frustum of a cone, as clearly shown in Figs. 1 and 8. This conical guard insures that oil that may escape at the 30 end of the axle-box will drop within the flange and be retained there, the outer face 35 of the guard being always clean and free from oil, even when no cap is used, thus removing all danger of soiling the clothing by contact with the outer flange of the wheel. In Fig. 1 I have shown the opening in the 40 guard as closed by a rubber cap 34, and in Fig. 5 I have shown it as closed by a metal cap 35.

The form illustrated in Fig. 10 differs from the other form in that the ordinary style of 45 return-bend spokes is used—that is to say, the mid-length of the piece of wire from which a pair of spokes is formed is simply a return-bend that is an outward or convex curve, as at 37. In this form the circumferential 50 groove is used as before; but instead of radial grooves to receive the spokes the inner ends of the spokes lie in curved grooves 38, which correspond with the curvature of the return-bend of the spoke and which intersect the circumferential grooves, the ends of 55 the curved grooves extending to the edge of the disk, as clearly shown.

In Fig. 1 I have shown an assembled barrel-hub in connection with what is termed a 60 "nutless" axle. The inner end of the axle-box is extended inward and has rigidly secured thereto a flanged sleeve 39, the flange of which is engaged by a spring-catch 40 to retain the wheel in place upon the axle.

65 In Fig. 8 I have shown an assembled bar-

rel-hub in connection with what is termed a "nut-axle." In this form the forward end of the axle is extended and provided with a thread 41, which is engaged by a nut 42, which just passes within the central opening 70 32 in the outer flange. It will thus be seen that either the inner or outer flanges are adapted without change to be used either with or without hub-barrels to make what are termed "barrel-hubs" and upon either 75 nut or nutless axles. As already stated, what I have termed "outer" flanges may be used at either end of the hub, if preferred, and if an oil-guard is not required inner flanges may be used at either end of the hub. 80

Having thus described my invention, I claim—

1. A hub-flange comprising an inner disk having a recess in its face to receive the end of a hub-barrel and an outer disk having 85 tongues curved over the edge of the inner disk to lock the disks and the spokes in place.

2. A hub-flange consisting of an inner disk having grooves which receive and support the inner ends of return-bend spokes and an 90 outer disk having notches to receive the spokes and tongues which curve over the edge of the inner disk to lock the disks and the spokes in place.

3. A hub-flange consisting of an inner disk 95 having in one side a recess to receive the end of a hub-barrel and in the other side grooves to receive the inner ends of return-bend spokes and an outer disk having notches which receive the spokes and tongues which 100 curve over the edge of the inner disk to lock the disks and spokes in place.

4. A hub-flange consisting of an inner disk having a circumferential groove and leading therefrom radial grooves which receive the inner ends of return-bend spokes, the walls of the grooves supporting the spokes, and an outer disk having tongues between which the spokes pass and which curve over the edge of the inner disk to lock the disks and spokes 110 in place.

5. In a hub-flange the combination with an inner disk having a circumferential groove and radial grooves leading therefrom, and return-bend spokes having inward curves 115 corresponding with the circumferential groove, of an outer disk having tongues between which the spokes lie and which curve over the edge of the inner disk to lock the spokes and disks in place.

6. A hub-flange consisting of an inner disk having a sleeve, in one side a recess to receive the end of a hub-barrel and in the other side grooves to receive return-bend spokes and an outer disk having a central opening, an outwardly - turned conical oil-guard, tongues which receive the spokes between them and curve over the edge of the inner disk and a cap closing the opening in the oil-guard. 125

7. A hub-flange consisting of an inner disk 130

having a sleeve with a recess in one side to receive the end of a hub-barrel, and an outer disk having a central opening, an outwardly-turned conical oil-guard, tongues which receive the spokes between them and curve over the edge of the inner disk and a cap closing the opening in the oil-guard.

In testimony whereof I affix my signature in presence of two witnesses.
